Primary Examiner — Brett Miller

Assistant Examiner — Mary Anne Arntzen

(74) Attorney, Agent, or Firm — Mintz, Levin, Cohn, Ferris, Glovsky and Popeo, P.C.

CLAIM

The ornamental design for a temperature probe holder, as shown and described.

DESCRIPTION

FIG. 1 is a front perspective view of the temperature probe;

FIG. 2 is a front view thereof;

FIG. 3 is a rear view of thereof;

FIG. 4 is a right view thereof;

FIG. 5 is a left view thereof;

FIG. 6 is a top view of thereof;

FIG. 7 is a bottom view thereof; and,

FIG. 8 is a bottom perspective view thereof.

The broken lines shown in the figures show features of the temperature probe holder that form no part of the claimed design.

1 Claim, 7 Drawing Sheets
